UNITED STATES PATENT OFFICE.

JOHN L. NEEDHAM, OF CHICAGO, ILLINOIS, ASSIGNOR TO THE BOYE NEEDLE COMPANY,
OF CHICAGO, ILLINOIS, A CORPORATION OF ILLINOIS.

NEEDLE-MAKING MACHINE.

1,248,152.

Specification of Letters Patent. Patented Nov. 27, 1917.

Application filed January 26, 1917. Serial No. 144,577.

To all whom it may concern:

Be it known that I, JOHN L. NEEDHAM, a citizen of the United States, residing at Chicago, in the county of Cook and State 5 of Illinois, have invented a new and useful Improvement in Needle-Making Machines, of which the following is a specification.

This invention relates particularly to needle-making machines; and the primary 10 object is to provide an improved machine which is especially useful in the manufacture of crochet needles.

The invention is illustrated in its preferred embodiment in the accompanying 15 drawings, in which—

Figure 1 represents a front elevational view of a needle-making machine constructed in accordance with the invention, the driving wheel being shown brokenly; Fig. 2 is a 20 sectional view taken as indicated at line 2 of Fig. 1 and showing the detail of the friction device which is used for elevating and depressing a shifttable needle carrier; Fig. 3, a horizontal sectional view taken as indicated at line 3 of Fig. 1; Fig. 4, a broken 25 sectional view parallel with the front side of the machine, the section being taken as indicated at line 4 of Fig. 3; Fig. 5, a broken sectional view in the same plane as Fig. 4, but showing the upper dies; Fig. 6, a broken sectional view similar to Fig. 4, 30 but showing the needle carrier in depressed position, whereas Fig. 4 shows the same in elevated position; Fig. 7, a vertical sectional view through the bed-plate of the 35 machine and perpendicular to the front side of the machine, the section being taken at line 7 of Fig. 3; Fig. 8, a broken sectional view taken at line 8 of Fig. 3, and showing 40 the needle carrier associated with the finishing die of the machine; Fig. 9, a broken side elevational view of the machine, the view being taken as indicated at line 9 of Fig. 1; Fig. 10, a broken lower face view of the 45 upper die-plate and the dies carried thereby; Fig. 11, a broken plan view of the lower die-plate and the dies carried thereby; Fig. 12, an enlarged vertical sectional view illustrating the first hook-forming operation, this 50 operation being performed by the dies shown near the lower portions of Figs. 10 and 11; Fig. 13, a broken view of the operative end of the crochet needle after the first hook-forming operation; Fig. 14, a

view illustrating the manner in which the 55 web within the hook is removed by the dies directly opposite Fig. 14 in Figs. 10 and 11; Fig. 15, a view of the operative end of the crochet needle after the trimming operation performed by the dies which are shown near 60 the upper portions of Figs. 10 and 11; and Fig. 16, a fragmentary view, showing the reduced end portion of the blank from which the operative end of the crochet needle is 65 formed, starting with the operation illustrated in Figs. 12 and 13.

It may be explained here that in the operation of the improved machine, preparatory formed blanks are fed in succession into the machine, each blank being advanced, step by step, and die to die, in the normal operation, three blanks, at different stages of completion, being operated upon by the dies at each descent of the upper cross-head.

The upper cross-head carries a depending cam which actuates a slide that oscillates a horizontal lever which operates a forwardly and rearwardly moving slide. The last mentioned slide is equipped with a pair of forks (Fig. 7) which engage laterally-projecting studs with which the needle-carrier or transferring device is equipped. The needle-carrier is shifted forwardly and rearwardly by the last mentioned slide, and 75 is raised and lowered by means of a cross-head (Figs. 6 and 7), said cross-head being actuated by the arm carried by a stem operated by the friction device carried by the upper die-plate, as illustrated in Figs. 80 1 and 2. Thus, the needle-carrier rises, lifts the needle from the stationary jaws with which the bed-plate is equipped, shifts the needles rearwardly to their new position, is lowered, makes a forward movement, and 85 then is lifted to repeat the cycle.

Describing the preferred construction which is illustrated, A represents the frame of the machine which is provided with a bed-plate A¹; B, the main cross-head of the machine, which carries the upper die-plate B¹; C, the drive-shaft, equipped with a driving-pulley C¹, whose connection with the driving-shaft is controlled by clutch mechanism C²; D a lower die-block fixedly secured to the bed-plate A¹; D¹, an upper die-block fixedly secured to the plate B¹, which is carried by the cross-head B; E, a guide-block

fixedly secured to the bed-plate A¹ and disposed parallel with the die-block D; F, a stationary needle-holder carried by the bed-plate A¹ and disposed a short distance from the die-block D, the member F being provided with a series of needle-receiving slots, and thus affording stationary needle-holding jaws; F¹, a stationary needle support, fixedly mounted on the guide-block E and having a series of slots or jaws corresponding with the slots of the member F; G, a needle-carrier, or needle-transferring device which is free to be lifted and depressed and also to be moved forwardly and back, the carrier G being disposed between the guide-block E and the stationary needle-holder F; H (Fig. 7), a slide through the medium of which the carrier G is moved forwardly and rearwardly, the slide H being actuated by a horizontally-disposed lever H¹ mounted on the bed-plate; I, a vertically movable horizontal bar with which the carrier G has tongue and groove connection, permitting the carrier to move forward and back, notwithstanding the bar I is capable only of being raised and lowered by parallel movement; I¹, a cross-head connected by bolts with the bar I, said bolts extending through perforations in the bed-plate A¹; I², an arm carrying the cross-head I¹; I³, a vertical stem which carries the arm I² and which has telescopic connection with a friction device I⁴ surmounting one end of the bed-plate B¹, to which it is fixedly secured; J, a forwardly and rearwardly movable slide which serves to actuate the lever H¹, the slide J being equipped with a cam-member J¹ (Fig. 9) which is actuated by a cam-member J² carried by the upper die-plate B¹. As appears from Figs. 10 and 11, the lower and upper die-blocks D, D¹, are equipped with pairs of dies, K, K¹ and L, L¹, and M, M¹, these pairs of dies serving, in the order named, to accomplish the results illustrated, respectively, in Figs. 13, 14 and 15.

As has been indicated, the blanks for the crochet needles N are preparatorily formed in a suitable swaging machine or swaging machines, in which preparatory operations the blanks are provided with a flattened portion 1 and a reduced extremity 1^a, the hook of the crochet needle being afterward formed in the present machine by operating upon the free extremity of the reduced portion 1^a of the needle-blank.

The frame A of the machine may be of any desired construction, and the cross-head B may be operated by any suitable mechanism. Preferably the machine is of ordinary press construction, and, preferably, the bed-plate A¹ inclines rearwardly and downwardly somewhat, while the guides for the cross-head B incline upwardly and rearwardly somewhat so as to be at right angles

to the bed-plate. The inclination mentioned is not illustrated, however.

The pulley C¹ runs loose on the shaft C, but may be coupled to the shaft through the medium of the clutch C², which may be controlled by a foot-lever (not shown). The bed-plate A¹ is fitted with upwardly-extending guide-posts 2 and 3 which extend through guide-perforations with which the die-plate B¹ is provided. The die-block D¹ is fitted with depending guide-pins 4 and 5 which work through perforations 4^a and 5^a in the die-block D, as indicated in Fig. 3.

The die-block D is securely fastened to the bed-plate A¹ by any suitable means (not shown); also the die-block D¹ is securely attached to the moving die-plate B¹ by suitable securing means (not shown).

The guide-block E is firmly secured to the bed-plate A¹ and is equipped on the side 85 adjacent the needle-carrier G, with guides 6 provided with slots 7 in which the bar portions 7^a of the carrier G are confined (Fig. 7), these slots 7 being of sufficient vertical depth to permit up and down movement of the carrier G, the carrier being capable of forward and rearward movement, also.

The stationary needle support F, which also affords a guide-wall for one portion of 95 the carrier G, presents a vertical surface opposed to the inner lateral face of the guide-block E and spaced a sufficient distance therefrom to accommodate the carrier G. The carrier G comprises, in addition to the bar 7^a, whose ends are reduced to permit vertical movement in the slots 6 of the guide-member 7, a plurality of U-shaped members 8, 9 and 10 (Figs. 6 and 7), which, as shown in Fig. 7, have one set of their arms 105 firmly attached to the bar 7^a of the carrier, the other set of arms bearing against the adjacent surface of the stationary member F. The upper ends of the arms of the carrier members 8, 9 and 10 are provided with 110 slots 11, adapted to accommodate needles. The stationary member F is provided in its upper edge-portion with vertical slots 12. These slots, as well as the slots 11 of the adjacent arms of the carrier, are narrow and 115 adapted to receive the flattened portions 1 of the needle-shafts. The stationary needle-supporting member F¹ is a U-shaped member mounted on the guide-block E. The outer flange is of sufficient height to afford 120 a guide-wall for the inoperative ends of the crochet needles. The inner flange is provided with vertical slots 13 which correspond in position with the slots 12 of the member F.

The carrier G is directly actuated in its forward and rearward movements by the slide H, and is raised and lowered by the bar I. Accordingly, the bar 7^a of the carrier has tongue and groove connection 14 130

with the bar 7^a of the carrier; and the slide H, which moves in a guide 15 in the bed-plate A¹, is equipped with a pair of upwardly-extending forks 16 (Fig. 7) which engage studs 17 which project laterally from the bar 7^a of the carrier G.

The horizontal portion of the slide H is provided on its upper surface with a stud 18 which is engaged by the forked end of the lever H¹ which extends over the horizontal portion of said member H. The lever H¹ is pivotally connected with the bed-plate A¹ by a screw bolt 19 which has a flanged upper end (Fig. 6).

15 The vertically movable bar I, with which the bar 7^a of the carrier G has sliding connection, is fitted with depending pins 20 which pass through perforations in the bed-plate and have their lower ends firmly secured to the cross-head I¹. The cross-head I¹, as appears from Fig. 6, is carried by the arm I² which is firmly secured to the vertical moving stem I³. As appears from Figs. 1 and 2, the stem I³ has telescopic connection with the friction device I⁴ mounted on the plate B¹. The device I⁴ comprises a split barrel 21 provided with clamping screws 22, the bore of the barrel 21 being fitted with friction material 23. By this form of slip-joint connection, the friction between the stem I³ and the barrel 21 may be regulated at will.

25 The slide J moves in a guide-slot in the bed-plate, being confined therein by guide-blocks 24. The upwardly-projecting arm or stem J¹ of the slide J is provided with a cam-slot having an inclined intermediate portion 25, a vertical upper portion 26, and a vertical lower portion 27. The member J² carried by the cross-head of the plate B¹ is equipped with a stud or roller 28 which works in the cam-slot.

30 As appears from Figs. 10 and 11, the dies K and K¹ are provided with recesses which are of such shape as to produce the contour of the hook 1^b of the crochet needle. In this operation, however, the dies produce a web or fin 1^c (Fig. 13). The die L is provided with a triangular recess 29; and the die L¹ is equipped with a triangular punch 29^a which corresponds with the recess 29. These dies are adapted to remove that portion of the fin which is within the hook, in the manner illustrated in Fig. 14. This operation can be performed without injuring the hook, while the remainder of the web 1^c serves to strengthen the hook.

35 Thereafter, the remainder of the fin 1^c is removed by the dies M and M¹. For this purpose, the die M is provided with a recess or perforation 30 which corresponds in shape with the hook shown in Fig. 15; and the die M¹ is provided with a punch 30^a, which corresponds in shape with the shape of the hook. The punch 30^a is adapted to force the

needle through the female die 30, in which operation the portion of the web exterior to the hook is sheared off. The die M is shown equipped with a guide-member 31 having two forks provided with upturned flanges 70 31^a separated by a space adapted to guide the hook portion of the needle to the die, as the needle is lowered. A similar guide may be provided for the die L, if desired.

40 As appears from Fig. 4, the die L, the die-block D, and the bed-plate A¹ are provided with a vertical channel or perforation 32 through which the materials trimmed from the needle in this operation are discharged. In their travel through the machine, the crochet needles are engaged by spring-hold pressure-member 33, carried by a spring-arm 33^a, which, as appears from Figs. 3 and 7, is carried by a bracket-member 33^b mounted on the bed-plate A¹. The function of the spring-hold pressure-member 33 is to insure the proper seating of the crochet needles in the jaws of the carrier or the stationary jaws, as the case may be.

45 When the needle-blank is inserted by the operator in the first pair of stationary jaws, the operator takes care to have the end of the shank of the needle bear against the rear flange of the holder F¹. To aid in holding the needle-blank in its first position, there is provided a spring-jaw or gripper 34 (Figs. 3 and 7) which is mounted on the front guide-block 6.

50 As has been indicated, the operator, in inserting the needle-blank, takes care that the base end of the shank bears against the rear flange of the combination guide and holder F¹. To insure such contact at the other points of operation there are provided vertical leaf-springs 35 and 36 (Figs. 3 and 6) 105 whose upper ends are disposed opposite the slots 12 of the stationary needle-holder or jaw-member F. The lower ends of the springs 35 are securely attached to a block 37 secured to the bed-plate. The upper ends 110 are curved rearwardly somewhat and adapted to engage the lower edges of the flattened vertical portions 1 of the needles, as appears from Fig. 6, so that when the needles are lowered into the slots 12 and 13 of the stationary jaws as the carrier descends preparatory to making a forward movement, the pressure of the pressure-member 33 will serve to cause the upper ends of the springs 35 to move rearwardly somewhat, so that the 115 needle will be shifted rearwardly or maintained in contact with the rear flange of the stationary holder and guide-member F¹.

55 It has been explained that in the final trimming operation, the needle is forced downwardly into the hook-shaped opening 30 of the female die M. To lift the needle again, there is provided (Fig. 8) a tappet 38 having a head portion 38^a corresponding in shape with the opening 30. The tappet 120

38 extends through the die-block B and bed-plate A¹ and is actuated by an arm 39 carried by the cross-head I¹ (Figs. 6 and 7).

It should be explained that the horizontal lever H¹ is provided with a rounded head 40 which engages a slot 41 with which the slide J is provided, so that the lever H¹ will be oscillated about its pivot 19 as the slide J reciprocates; also that the slide H which reciprocates the carrier G forwardly and rearwardly is confined in the guide-slot 15 of the bed-plate by a guide-block 42, which is secured to the bed-plate by screws 43 (Figs. 3 and 4); and, finally, that the upper die-block D¹ is equipped with a spring-held stripper 44 (Fig. 5), through which the punches work.

Briefly, the operation is as follows: The operator sets the machine in motion by depressing the releasing member of the clutch C², which couples the shaft C with the driving-pulley C¹. The operator places the preparatorily-formed needle-blanks, one at a time, in the first set of jaws or slots 12 and 13 of the stationary needle-holders F and F¹. In inserting the needle-blank it is pressed by the operator into the spring-jaw 34 which is provided at the initial point of operation. Assuming the machine to be in full operation, the dies perform operations (of three different stages) upon three needle blanks at each descent of the cross-head I. As the cross-head rises, the guide-member I is lifted through the medium of the cross-head I¹ which is carried by the frictionally-lifted stem I³.

While this action occurs, the pin 28 of the cam J² moves idly in the lower vertical portion 27 of the guide-slot of the cam-arm J¹. Thereafter, the stem I³ slips through the friction-device I⁴; and the needle-carrier G being now in elevated position is shifted rearwardly through the medium of the slide H which is actuated by the lever H¹, it being understood that the cam-stud 28 is at this period actuating the slide G by working in the inclined portion 25 of the cam-slot of the arm J¹. After the carrier reaches the rearward limit of its travel, the cam-stud moves idly in the upper vertical portion 26 of the cam-slot. In the descent of the cross-head, the stem I³ is first disposed to lower the guide-member I and therewith the carrier G, after which the stem I³ slips through the friction device I⁴. In this portion of the movement, the cam-stud 28 moves idly in the upper vertical portion 26 of the cam-slot in the arm J¹; and after the needle-carrier has been lowered so that its jaws will clear the needles which have now been deposited in the stationary jaws, the cam-stud 28 operates through the inclined portion 25 of the cam-slot, thereby shifting the slide J rearwardly and moving the lower carrier forwardly. It may be

noted that the slippage mentioned occurs when the cross-head I¹ encounters the bed A¹ on the up-stroke, and when the member I encounters said bed on the down-stroke of the machine.

In their step-by-step movement through the machine, the needle-blanks are operated upon by the pairs of dies, in succession; and, finally, the needles are dropped by the carrier upon the die-block D and guide-block E, from which they may slide or tumble in a suitable receptacle (not shown).

It will be recalled, in this connection, that the bed-plate of a machine ordinarily inclines rearwardly and downwardly somewhat, so that there is no difficulty in effecting discharge of the needles from the machine.

The machine described is simple and durable, of large capacity, and well adapted to its purpose. By the use of the machine perfect crochet needles may be rapidly and cheaply produced.

The foregoing detailed description has been given for clearness of understanding only and no unnecessary limitation should be understood therefrom, but the appended claims should be construed as broadly as permissible, in view of the prior art.

What I regard as new and desire to secure by Letters Patent is—

1. In a machine of the character set forth, the combination of a bed equipped with a row of dies, a cross-head equipped with a row of companion dies, a series of stationary needle-holding devices corresponding in position with the series of stationary dies, a needle-carrier adapted to vertical movement and also to rearward and forward movement, means carried by the cross-head serving in the raising and lowering of said needle-carrier, and means carried by the cross-head serving in the operation of shifting said carrier rearwardly and forwardly.

2. In a machine of the character set forth, the combination of a bed, a series of hook-forming and trimming dies mounted thereon, a reciprocating cross-head, equipped with a series of cooperating hook-forming and trimming dies, a series of stationary needle-holding devices arranged opposite the several stationary dies, a needle-carrier equipped with a plurality of needle-holding devices adapted to be brought into registration with said stationary needle-holding devices, and devices actuated by said cross-head and serving to raise said needle-carrier, shift the same rearwardly, depress said needle-carrier and shift the same forwardly.

3. In a machine of the character set forth, the combination of a series of stationary dies, a reciprocating cross-head equipped with a plurality of companion dies, a series of stationary needle-holding jaws, a needle-carrier equipped with a corresponding series

of needle-holding jaws, a friction-actuated device connected with the cross-head and serving to elevate said needle-carrier, and means for reciprocating the needle-carrier 5 forwardly and rearwardly.

4. In a machine of the character set forth, the combination of a series of stationary dies, a reciprocating cross-head equipped with a plurality of companion dies, a series 10 of stationary needle-holding jaws, a needle-carrier equipped with a corresponding series of needle-holding jaws, a friction-actuated device connected with the cross-head and serving to elevate said needle-carrier, and 15 mechanism actuated by said cross-head for shifting the needle-carrier forwardly and rearwardly.

5. In a machine of the character set forth, the combination of a series of stationary 20 dies, a reciprocating cross-head equipped with a plurality of companion dies, a series of stationary needle-holding jaws, a needle-carrier equipped with a corresponding series of needle-holding jaws, a friction-actuated 25 device connected with the cross-head and serving to elevate said needle-carrier, a lever serving to shift said carrier rearwardly and forwardly, a slide serving to actuate said lever, and a cam device actuated by the 30 cross-head and serving to actuate said slide.

6. In a machine of the character set forth, the combination of a bed-plate equipped with a series of hook-forming and trimming dies, a reciprocating cross-head equipped 35 with a series of companion dies, a series of stationary needle-holding jaws at one side of and corresponding in position with said stationary dies, a needle-carrier provided with a series of jaws corresponding with 40 said first-named jaws, means for raising and lowering the needle-carrier, means for reciprocating the needle-carrier rearwardly and forwardly, and a pressure-member adapted to maintain the needles in proper 45 position in the jaws as the needles are progressively carried through the machine.

7. In a machine of the character set forth, the combination of a bed equipped with a 50 series of dies, a reciprocating cross-head equipped with a series of companion dies, a stationary plate equipped at its upper portion with a series of narrow jaws adapted to engage the flattened portions of needles, a stationary member at some distance from 55 said plate and equipped with a plurality of jaws adapted to receive the shanks of the needles, an interposed needle-carrier equipped with a plurality of jaws corresponding with said first-named jaws, means 60 for elevating and depressing the needle-carrier, and means for shifting the needle-carrier rearwardly and forwardly.

8. In a machine of the character set forth, the combination of a bed equipped with a 65 series of dies, a reciprocating cross-head

equipped with a series of companion dies, a stationary jaw member parallel with said first-named dies and provided with a series of jaw recesses, a series of spring-fingers associated with said jaw recesses and adapted 70 to serve in positioning the needles, a needle-carrier equipped with a plurality of needle-receiving jaws, means for elevating and depressing said carrier, means for shifting said carrier rearwardly and forwardly, and a pressure-member operating to 75 depress the needles and coöperating with said fingers in positioning the needles.

9. In a machine of the character set forth, the combination of a bed equipped with a 80 series of dies, a reciprocating cross-head equipped with a series of companion dies, a stationary needle-holder equipped with a series of jaw recesses corresponding in position with and close to said stationary dies, 85 spring-fingers corresponding with said recesses, a stationary needle-holder at a distance from said first-named needle-holder and provided with a plurality of corresponding jaw recesses and equipped with a guide-flange, a needle-carrier equipped with a series of jaw recesses adapted to register with the jaw recesses of said stationary needle-holders, means for raising and lowering 90 the carrier and reciprocating the same, and a pressure-member adapted to bear on the needles and to coöperate with said spring-fingers in positioning the needles so that the extremities of the shanks will bear 95 against said guide-flange.

10. In a machine of the character set forth, the combination of a bed-plate, a rearwardly-extending die-block mounted thereon and equipped with a series of dies, a reciprocating cross-head equipped with a series of companion dies, a guide-block parallel with said die-block and separated therefrom by a space, a stationary needle-holder disposed near said die-block equipped with a series of jaw recesses, a needle-carrier interposed between said needle-holder and said guide-block and equipped with a plurality of jaw recesses, means for elevating and depressing said needle-carrier, and means for reciprocating said needle-carrier 100 rearwardly and forwardly.

11. In a machine of the character set forth, the combination of a bed-plate, a rearwardly-extending die-block mounted thereon and equipped with a series of dies, a reciprocating cross-head equipped with a series of companion dies, a guide-block parallel with said die-block and separated therefrom by a space, a stationary needle-holder disposed near said die-block and equipped 110 with a series of jaw recesses, a needle-carrier interposed between said needle-holder and said guide-block and equipped with a plurality of jaw recesses, a vertically movable guide-bar adjacent said guide-block, 115 120

125

means carried by said cross-head for elevating said guide-bar, slide connections between said needle-carrier and said guide-bar, and means actuated by said cross-head and serving to reciprocate said needle-carrier rearwardly and forwardly.

12. In a machine of the character set forth, the combination of a bed-plate, a rearwardly-extending die-block mounted thereon and equipped with a series of dies, a reciprocating cross-head equipped with a series of companion dies, a guide-block parallel with said die-block and separated therefrom by a space, a stationary needle-holder disposed near said die-block and equipped with a series of jaw recesses, a needle-carrier interposed between said needle-holder and said guide-block and equipped with a plurality of jaw recesses, a vertically movable guide-bar adjacent said guide-block, means carried by said cross-head for elevating said guide-bar, slide connections between said needle-carrier and said guide-bar, a slide mounted on the bed-plate and having slot and groove connection with a member of said needle-carrier, a lever serving to actuate said slide, a slide serving to actuate said lever, and a cam-device carried by said cross-head and serving to actuate said last-named slide.

13. In a machine of the character set forth, the combination of a bed-plate carrying a die-block equipped with a series of dies, a reciprocating cross-head equipped with a series of companion dies, a guide-block mounted on said bed-plate parallel with said die-block, a vertically movable guide-bar adjacent said die-block, a needle-carrier disposed between the die-block and guide-block and having a member slidably connected with said guide-bar, means for raising and lowering said guide-bar provided with a stem having friction connec-

tions with said cross-head, a slide disposed beneath said needle-carrier and having a groove and stud connection therewith, a stationary needle-holder adjacent said die-block, a lever serving to actuate said slide, and actuating means for said lever, including a member carried by said cross-head.

14. In a machine of the character set forth, the combination with stationary needle-holding members provided with a series of jaw recesses, a coöperating needle-carrier provided with a series of jaw recesses adapted to register with said first-named jaw recesses, means for reciprocating said needle-carrier forwardly and rearwardly, a member with which said needle-carrier is slidably connected, and means for elevating and depressing said member, including a stem and a reciprocating friction device engaging said stem.

15. In a machine of the character set forth, the combination with stationary needle-holders provided with a series of jaw recesses, an interposed needle-carrier provided with a series of jaw recesses, a frictionally movable guide-bar with which said carrier is slidably connected, a slide adapted to reciprocate said carrier forwardly and rearwardly and having vertical slot and stud connections with said carrier, means for reciprocating said slide, a head carrying said guide-bar, a substantially vertical stem carrying said head, and a reciprocating friction device engaging said stem.

16. In a machine of the character set forth, a vertically movable guide-bar, a friction-actuated member serving to elevate and depress said guide-bar, a reciprocating friction device serving to actuate said member, a carrier slidably connected with said guide-bar, and means for reciprocating said carrier.

JOHN L. NEEDHAM.

Copies of this patent may be obtained for five cents each, by addressing the "Commissioner of Patents, Washington, D. C."
